CLAIM

The ornamental design for a shredding machine for recycling, as shown and described.

DESCRIPTION

FIG. 1 is a perspective view of the shredding machine for recycling showing my new design;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof; and,

FIG. 7 is a bottom view thereof.

FIG. 1.

FIG. 6.

FIG. 2.

FIG. 4.

FIG. 3.
